and
Alexander Jameson,
By W. H. Lockwood ^{Attorney}

UNITED STATES PATENT OFFICE.

FRANK J. DAVIS AND ALEXANDER JAMESON, OF INDIANAPOLIS, INDIANA, ASSIGNORS, BY DIRECT AND MESNE ASSIGNMENTS, OF SIXTEEN-FORTIETHS TO SAID JAMESON AND TEN-FORTIETHS TO SAID JAMESON, TRUSTEE, THREE-FORTIETHS TO HARRY D. TUTEWILER, AND ELEVEN-FORTIETHS TO ISAAC DUNN, OF INDIANAPOLIS, INDIANA.

NON-REFILLABLE BOTTLE.

No. 825,263.

Specification of Letters Patent.

Patented July 3, 1906.

Application filed July 20, 1905. Serial No. 270,595.

To all whom it may concern:

Be it known that we, FRANK J. DAVIS and ALEXANDER JAMESON, of Indianapolis, county of Marion, and State of Indiana, have invented a certain new and useful Non-Refillable Bottle; and we do hereby declare that the following is a full, clear, and exact description thereof, reference being had to the accompanying drawings, in which like numerals refer to like parts.

The object of this invention is to provide a practical and successful means for closing a bottle so that it cannot be refilled.

The novel features herein will be understood from the accompanying drawings and the following description and claims.

In the drawings, Figure 1 is a central vertical section through a bottle filled with fluid and closed, the stopper being in elevation. Fig. 2 is a vertical section through a part of the neck of the bottle and stopper, parts being broken away. Fig. 3 is a plan view of the top disk. Fig. 4 is a plan view of the middle disk. Fig. 5 is a plan view of the bottom disk. Fig. 6 is a central section through the upper two disks, parts being broken away. Fig. 7 is a showing, partly in elevation and partly in section, of the upper two disks united by a simple rivet instead of by the means shown in Fig. 6. Fig. 8 is a horizontal section through the bottle on the line 8-8 of Fig. 2, the ball not being shown. Fig. 9 is a central vertical section of the neck of the bottle, showing a modified form of the stopper. Fig. 10 is a plan view of the upper disk shown in Fig. 9. Fig. 11 is a section on the line 11-11 of Fig. 9. Fig. 12 is a plan view of the lower disk shown in Fig. 9.

In the drawings, 20 represents a bottle in the neck of which there is an internal annular groove 21, adapted to receive the lower disk of the stopper. The body of this disk is made of glass 22, surrounded by a ring 23, of cork or other suitable material, that fits in the groove 21. The disk 22 is depressed with the cork about it until it reaches the groove 21 and springs into the groove, whereby the disk is held in place.

The disk 22 has in it the passage-ways 24, five being shown in Fig. 5. The disk has a depression surrounded by a flange 25 to pro-

vide a seat for a mica valve 26. This valve closes the holes 24 in the disk, and a ball 27 is placed in upon said valve to help in holding it in its closed position.

The mica valve is held down by a pair of lugs 28, extending from the middle disk 29, said lugs resting upon the disk at two points. Said disk has also two other lugs 30, that extend downward from it, that rest on the flange 25 and do not prevent the opening of the valve 26. The middle disk 29 is provided with an outlet-port 31 and an upwardly-extending rib 32, upon which the upper disk 33 is placed. Said upper disk is held in place with the middle disk by loose clamps 34 (shown in Fig. 6) and which fit in notches 37 in the middle and upper disks, as seen in Figs. 3 and 4. The upper disk has a smaller diameter than the lower disk or than the neck of the bottle, so that fluid or air may pass about it freely. It has a groove on its under side, whereby it fits tightly over the rib 32. These two disks 29 and 33 may be secured, as shown in Fig. 7, by a metal pin 38, extending down through central openings in said disks and the upper disk having a downwardly-extending collar 39 extending about the pin 38 and which spaces the upper disk from the middle disk.

A suitable air-inlet is provided by means of the air-tube 40, that passes through the lower disk 22 into a downwardly-extending hollow extension 41 from the middle disk 29. Said middle disk 29 is also provided above said extension 41 with an opening 42, adapted to receive the mica valve 43, mounted loosely about the rod 44, which is held in place by a plug 45, that fits in the extension 41. There is a secure connection made by cement or otherwise between the upper end of the air-tube 40 and the inside of the extension 41 of the middle disk and between the air-tube 40 and the lower disk, and in that way the middle disk is held down securely in place with relation to the lower disk, and by reason of the clamps 34 the middle disk holds the upper disk down in place, whereby the two upper disks cannot be removed, as the lower disk is securely seated in the neck of the bottle.

In operation the bottle is filled with liquid and the stopper is assembled and inserted in

the neck of the bottle until the lower disk is secured in the groove 21. When the bottle is inverted, the ball 27 leaves the mica valve 26, and the pressure of the fluid against the 5 valve opens it sufficiently to permit the fluid to escape rather freely, the fluid passing through the openings 24 in the lower disk and the openings 31 in the middle disk and around the upper disk. While the fluid is thus es-
 10 caping, air passes into the bottle through the air-tube 40, for the inverted position of the bottle opens the plug 45 and valve 43. The valve 43 is considerably less in diameter than the hole 42, in which it is located, so that air 15 will pass about it freely when it is not down in its seat. The mica valve 26 will prevent the refilling of the bottle, as it fits flat on the disk 22, and by reason of the peculiar capillary attraction between the water and the 20 mica valve on the one side and the glass disk on the other side a seal is effected. This would not occur with the disk made of leather or other porous material. Therefore mica is peculiarly adapted for this valve in this situa-
 25 tion, and said valve will close and remain closed without the ball 27. Said ball is merely a practical means and useful in weighting the mica valve while the bottle is standing on the shelf, as it may remain on the 30 shelf for a long time before it is emptied. Likewise the mica is indestructible and firm as a valve and the parts are so positioned and protect it so that it cannot be reached externally and injured. Chemicals externally ap-
 35 plied could not injure it, nor would it be affected by the contents of the bottle, nor will it injure the contents of the vessel; nor can the liquid be introduced through the air-tube 40, because of the valve 43 and plug 45.
 40 In the modified form shown in Figs. 9 and 12 the lower disk 50 is held in place by the cork ring 23 the same as in the other form. This disk has but one passage-way 51, and the upper end of the disk is extended up-
 45 wardly centrally and has a valve-seat inclined at about an angle of thirty degrees from the horizontal position. In this valve-seat a mica valve 52 is located, as shown in Fig. 9. The middle disk 54 has a central opening 55 through it somewhat irregular in form, and the internal surface has vertically-extending recesses 56 about its lower portion, as seen in 50 Figs. 9 and 11, so that when the bottle is inverted and the mica disk valve falls away from its seat somewhat the fluid will pass outward through the recesses 56. The ball 27 may be used upon the valve, if desired; but it is not necessary. The upper disk 57 is inclined substantially parallel with the valve-
 55 seat and has recesses 58 in its edges, so that there will be a passage-way between it and the neck of the bottle for the exit of the fluid. The plan of this disk is shown in Fig. 10. It is locked in with the middle disk by a down-
 60 ward extension 59, enlarged at its lower end,
 65

that fits in the corresponding recesses of the middle disk, as shown in Fig. 9. The upper part of the outlet-opening 55 in the middle disk is widened, so that the fluid may pass from it through the outlets 58 of the outer disk. 70 In this modified form the fluid will pass outward when the bottle is inverted, but not inward when in any position, because of the mica valve immediately closing on its seat.

What we claim as our invention, and de- 75 sire to secure by Letters Patent, is—

1. The combination with the neck of a bot-
 tle, of a disk secured therein with an opening 80 through it, a mica valve lying flat on said disk for closing said opening, means for hold-
 ing one edge of said valve permanently
 against the disk, and means to prevent ac-
 cess to said valve.

2. The combination with the neck of a bot-
 tle, of a disk secured therein with an opening 85 through it, a mica valve lying flat on said disk for closing said opening, means for hold-
 ing one edge of said valve permanently
 against the disk, a ball resting loosely upon
 said valve, and means to prevent access to 90
 said valve.

3. The combination with a bottle, of a disk
 secured therein having an opening through it
 and a substantially central depression upon 95 its upper side with an upwardly-extending
 flange surrounding said depression, a mica
 valve lying in said depression, and means
 bearing against one edge of said valve for
 holding it in place on said disk.

4. The combination with a bottle, of a 100 lower disk secured in the neck thereof and
 having an opening through it, a mica valve
 lying flatly upon the surface of said disk for
 closing said opening, another disk above the
 former and secured thereto, and lugs extend- 105
 ing downward from said upper disk that bear
 upon one edge of said valve.

5. The combination with a bottle, of a 110 lower disk secured in the neck thereof with
 an opening through it and a central depres-
 sion in its side with a surrounding flange, a
 mica valve lying loosely in said depression, a
 disk above the former and secured thereto, 115
 legs extending downward from said last-men-
 tioned disk and bearing upon one edge of
 said valve, and other legs extending down-
 ward from said last-mentioned disk and bearing
 upon the flange of the lower disk.

6. The combination with a bottle, of a 120 lower disk secured in the neck thereof having
 an opening through it, a mica valve for clos-
 ing said opening, an air-tube extending
 through said disk and above the same, an-
 other disk with an air passage-way through 125
 it and which is secured to the upper end of
 said air-tube, and legs extending down from
 said last-mentioned disk that bear upon the
 edge of said valve and hold it in position.

7. The combination with a bottle, of a 130 lower disk secured in the neck thereof with

- an opening through it, a mica valve lying upon said disk for closing said opening, a middle disk secured to said lower disk and having an outlet-opening, legs extending 5 down from said last-mentioned disk that bear upon the edge of said valve and hold it in position, an outer disk extending over the opening through the middle disk, and means for securing the outer disk to the middle disk.
- 10 8. The combination with a bottle, of a lower disk secured to the neck thereof and having an opening through it, a valve for closing said opening, a middle disk secured to the lower disk with an outlet through it and 15 having a plurality of notches in its periphery and an upwardly-extending projection, an outer disk of smaller diameter than the neck
- of the bottle mounted upon said projection from the middle disk and having notches in the periphery thereof corresponding with the 20 notches in the middle disk, and clamping-plates adapted to fit in the corresponding notches of said middle and outer disks with inwardly-extending ends for overlapping said disks substantially as shown for securing the 25 upper disk to the middle disk.

In witness whereof we have hereunto affixed our signatures in the presence of the witnesses herein named.

FRANK J. DAVIS.
ALEXANDER JAMESON.
